UNITED STATES PATENT OFFICE

153,797

DESIGN FOR A DISPLAY BOX

Jacques Heim, Paris, France

Application February 26, 1947, Serial No. 137,188

Term of patent 3½ years

(Cl. D80—5)

To all whom it may concern:

Be it known that I, Jacques Heim, a citizen of France, residing in Paris, France, have invented a new, original, and ornamental Design for a Display Box, of which the following is a specification, reference being had to the accompanying drawing, forming part thereof, wherein,

Figure 1 is a front perspective view of a display box, showing my new design in closed position.

Figure 2 is a view similar to Figure 1, showing the display box in open position.

The opposite side and rear of the display box are devoid of central ornamentation and are identical in appearance to the right side of the display box shown in Figure 1.

I claim:

The ornamental design for a display box, substantially as shown and described.

JACQUES HEIM.
